GLOW-PLUG FOR COMPRESSION-IGNITION ENGINES

Adolph F. Klingner and William H. Balentine,
Hellertown, Pa., assignors to Thomas A. Edison,
Incorporated, West Orange, N. J., a corporation
of New Jersey

Application June 23, 1950, Serial No. 169,810

2 Claims. (Cl. 219—32)

1

This invention relates to glow plugs of the kind used to initiate combustion of the fuel-air charges in compression-ignition engines while the engines are cold.

Compression-ignition engines, otherwise often times referred to as diesel engines, are hard to start when cold because each combustion-chamber wall then absorbs so much heat during the compression stroke that the compression temperature is not raised high enough to assure combustion. If combustion fails, or occurs late, destructive pounding and hammering of the working parts may occur to cause serious damage to the engine.

Glow plugs are provided to overcome this difficulty. These plugs have resistance elements which are placed in the combustion chamber and which are heated by an electric storage battery or the like to a glow temperature, which is a temperature sufficiently high to cause ignition of the fuel-air charges while the engine is cold. Although these resistance elements are so heated electrically only during the starting period, they have to be able to withstand the very high temperatures in the combustion chambers and the heavy engine vibration, encountered in normal engine operation.

It has been common to make the resistance elements of large, heavy wire which is capable of withstanding the engine vibration and the corrosive action of the hot combustion gases, without support or covering along the length thereof. However, such large resistance elements are objectionable from a size standpoint, and are not usable in many of the engines of modern design. Also, these large resistance elements have had to be connected in series to conserve the current drain on the battery. Such series connecting is very objectionable from the standpoint that if one resistance element should burn out then all of the glow plugs are disabled.

In order to make the resistance elements relatively small, and to provide them with sufficient resistance to enable them to be connected individually across the storage battery, in parallel with one another, they must be made of relatively fine heater wire. Such fine wire cannot withstand direct exposure to the combustion gases but must be protected by a case. Experience has shown that it is a very stringent design and construction requirement to provide a heater unit—a heater coil with a protective case—of small size, which unit has sufficient resistance to work across an automotive storage battery and

10 sufficient heating capability to heat the case to an ignition temperature, and which has yet sufficient durability to withstand over a long period the constant vibration, and the high heat and corrosive action of the combustion gases, encountered in modern compression-ignition engines.

15 Objects of the present invention are to provide design and construction improvements in a glow plug of the type having an encased heating element, which improvements enable the plug to be worked across a conventional storage battery and to be made of small size while having sufficient heating capability to cause ignition of the fuel-air charges while the engine is cold.

A further object is to provide such improved glow plug which is able to withstand for a period of 1000 hours or more the severe operating conditions of high temperature, corrosive action, pressure and vibration to which such plugs are subjected in modern compression-ignition engines.

20 These and other objects and features of our invention will be apparent from the following description and the appended claims, reference being had to the accompanying drawings, of which

25 Figure 1 is a side view, partly in elevation, and partly in section on a plane through the central axis, of a glow plug according to our invention;

Figure 2 is an axial-sectional view, to larger scale, of the lower active portion of the plug of Figure 1, showing various design and construction details of the heating unit of the present plug according to our invention;

30 Figure 3 is a cross sectional view taken on the line 3—3 of Figure 2 but showing the heating unit with the insulating filler removed; and

35 Figures 4 and 5 are end and side views respectively of a locking bushing used at the upper end of the plug to secure the central spindle to the housing.

40 The glow plug shown in Figure 1 comprises an externally-threaded shell 10 having an axial bore 10a through which extends a spindle 11. Inserted into the lower end of the bore 10a of the shell, against an internal shoulder 10b, and welded to the shell at 12, is a heater-unit case 13 having a heater winding 14 mounted therein. The innermost end of the coil is secured at 15 to the end wall of the case, and the other end of the coil is secured at 16 to the adjacent end of the spindle 11. The spindle is centered axially in the shell, and insulated electrically therefrom, by an insulating washer 17 at its inner end and by an

insulating bushing 18 at its upper end. The washer 17 is mounted against a flange 19 on the spindle and is drawn against an annular shoulder 20 in the shell by tension exerted upwardly on the spindle, this tension being produced by threading a nut 21 on the outer end portion of the spindle against the bushing 18. The bushing 18 is centered relative to the shell by having a tapered end portion 22 which fits into an outwardly-flared end portion 23 of the bore 10a in the shell. On the outer end of the spindle there is a knurled hand nut 24 for clamping a lead wire (not shown) between it and the nut 21.

The glow plug is mounted by threading the shell 10 into an internally-threaded opening provided in the cylinder head of the engine, the plug being threaded inwardly until the heater unit thereof is exposed to the combustion gases in the precombustion chamber of the respective cylinder of the engine. The energizing circuit for the plug is completed by connecting the spindle 11 to one terminal of the ignition battery by means of a lead wire (not shown), and by making a ground connection between the other terminal of the battery and the case 13 by way of the cylinder head and shell 10, it being herein unnecessary to show the engine parts referred to since the means of mounting the plug and of making its circuit connections are well understood.

If the engine is cold, the energizing or heater circuit of the plug is closed to heat the case 13 to a glow temperature before the engine is cranked. When the case is so heated, it will supply sufficient heat in the respective combustion chamber to compensate for the heat loss to the surrounding combustion chamber walls, and will assure ignition of the respective fuel-air charge as this charge is compressed. One such plug is provided for each cylinder so as to assure even starting and running of the engine during the warm-up period. When the engine has warmed up, the heating current to the plugs is cut off, but inasmuch as the heating units of the plugs are in the combustion chamber and are subjected continuously to the high temperature, corrosive action and pressure of the combustion gases, as well as to the vibration of the engine, so long as the engine is running, the plugs must be of very durable construction.

A first specific requirement of the present glow plug is that the case 13 be able to withstand the high temperature, corrosive action and pressure of the combustion gases in the engine cylinder. That this is a stringent requirement will be appreciated when it is realized that the case cannot have good heat conduction lengthwise thereof else the heater coil in the case will be unable to heat the case to the required temperature. Since the case must have poor heat conduction to the shell to which it is secured, it will acquire nearly the temperature of the combustion gases, and will be thus at a much higher temperature during normal engine operation than will be the surrounding combustion chamber walls which are cooled by water jackets, air flow, etc. A low heat conduction lengthwise of the case, together with an ability to withstand the high gas pressure in the engine cylinders, requires a case wall thickness of the order of .032". Extensive tests have shown that a case cast to shape is far more satisfactory than one machined from solid bar stock because a cast case has a tougher grain structure and is more resistant to corrosion. It is found that suitable alloys for the case comprise

iron, cobalt, nickel, chromium, tungsten and carbon as basic ingredients and that certain improved properties are obtained when such alloys contain minor percentages—i. e., about 3% or less—of one or more of the ingredients: molybdenum, columbium and nitrogen. A highly-preferred material for the case is Haynes Stellite "Multimet" alloy, designated N-155, the composition of which is: 0.30-0.40 C; 18.0-22.5 Cr; 18.0-22.0 Ni; 2.75-3.75 Mo; 0.75-1.50 Cb; 2.0-3.0 W; 18.0-22.0 Co; 0.10-0.20 N and balance Fe. Extensive tests have shown that this alloy is highly resistant to oxidation at temperatures up to 2000° F. and is highly resistant to acid attack by the fuel combustion products. Also, it has high strength at high temperatures making it suitable to withstand the compression pressures and temperatures inherent in the cylinders of diesel engines.

In order that the glow plug will positively initiate ignition when the engine is cold, the heater winding 14 must be capable of heating the case 13 to a glow temperature of the order of 1840° F. Since the melting temperature of available heater wire is only a few hundred degrees higher than this temperature, it follows that good heat conduction is required between the winding and the case; yet, it is also required that the heater winding be electrically insulated from the case. These conditions have been met by lining the inner peripheral wall of the case 13 with a thin tubing of mica having the length of the case and a diameter such that it will just fit snugly into the case. This mica tubing is made of sheet stock of the order of .001" thick wound into tubular form to a wall thickness of the order of .005" to .007". The thickness of the tubing is very critical since it is found that thicknesses of less than .005" are not durable enough to withstand the engine vibration for the required life of 1000 hours under the extreme heat conditions encountered in normal engine operation. On the other hand, thicknesses substantially greater than .007", say .01" or more, will cause the heat conduction between the heater coil and the case to be so reduced as to make it impossible to heat the case to the required temperature.

When the heater unit is small and the heater coil is to work from the full voltage of an automotive storage battery, the typical voltage of which for diesel engines is 12 volts, the heater wire must be very thin and must be supported firmly in the case so that the engine vibration will not loosen it and cause shorts or opens to develop. Typical present-day sizes of the heater case 13 are $\frac{1}{8}$ " to $\frac{1}{4}$ " outside diameter and 1" to $1\frac{1}{2}$ " length. To heat the case to the desired glow temperature above mentioned, from a voltage source of 12 volts, approximately 72 watts of electrical power must be expended in the heater winding and the winding must have approximately 2 ohms resistance. These requirements have been met satisfactorily by using a heater coil having of the order of 20 turns of No. 23 wire wound in a cylindrical helix of about $\frac{3}{4}$ " length, with even spacing between successive turns. The diameter of the coil is made such that the coil will just fit easily into the mica tubing which lines the inside wall of the case. Even spacing between turns and easy fitting into the case are very important so that when the winding is installed, the spacing between the terminals and the inner end portion of the heater coil will not be reduced to cause possible short-

ing between turns with resultant burn-out and shortening of life.

As abovementioned, the inner end of the heater coil is connected at 15 to the end wall of the case so as to complete the electric circuit of the heater coil by way of the case and shell of the glow plug. This joint between the coil and case is very critical. It must be a mechanically strong joint to withstand the intense heat and vibration of the engine; and it must be a low-resistance joint so that the heating current will not here produce a "hot spot" and cause burn-out and shortening of life. To meet these requirements satisfactorily, a bead 27 preferably of stainless steel which is for instance globular or tubular in shape, a tubular shape being preferred and being shown in Figure 3, is threaded onto the inner end of the coil, and this inner end is bent inwardly substantially on a diameter line of the coil so that the bead is centered at the axis of the coil and lies against the end wall of the case after the coil is installed. A spot-welding electrode (not shown) is then inserted into the case against this bead and is fed a timed impulse of heavy current to weld the bead simultaneously to the wire and to the end wall of the case. At this stage in the assembly operation, the end lead wire 26 of the heater coil, at the outer end of the case, is extended outwardly along the wall of the case so as not to obstruct access to the interior of the coil. Preferably, the welding electrode is provided with a concave end face so that it will impart an oval shape to the bead (Figure 2) during the welding operation. This manner of forming the joint 15 between the heater coil and the case is important in realizing the durability of construction required to obtain the desired life under the stringent conditions in which the glow plug is operated.

in place in the case, and to afford good heat con-

In order to hold the heater-coil turns firmly in place in the case, and to afford good heat conduction between the turns and the mica insulation lining the case, a layer 25 of chemically-setting ceramic cement is placed between the turns and onto the insulating tubing after the coil is inserted. This allows the cement to be installed easily as by means of a small brush. Preferably, a quick-drying cement is used. A suitable cement comprises aluminum oxide mixed with quick-drying agents of magnesium fluosilicate and sodium silicate and is available commercially as Sauereisen Cement No. 21. This cement bonds the coil turns firmly in the mica tubing, has good heat conduction and is able to withstand the intense heat to which the heater unit of the glow plug is subjected.

After the heater coil is welded to the case and the coil is cemented in place in the manner above described, the inner space of the coil is filled with a powdered ceramic insulation 28, preferably of an alkaline metal earth compound such as aluminum oxide. This powder is tamped firmly into the case to a level suitably beyond the outer end of the coil but not so as to completely fill the case. The outer lead wire is then bent so as to extend axially out of the case as shown by full lines in Figure 2, and the remaining end space of the case is filled with ceramic cement 29 which may be a cement such as the cement 25 hereinbefore described. The next step in the construction of the present glow plug is to make the joint 16 between the outer lead wire 26 of the heater coil and the spindle 11. This joint is made by inserting the wire 26 into an axial open-

ing in the spindle and thereafter welding it in place. It is important that the lead wire 26 have a slack length between the spindle and the case so that tension which may be exerted on the spindle will not put strain on the heater coil assembly to dislodge or loosen it in the case. This slack is provided by giving the lead wire a kink 30 as shown in Figure 2.

After the step just described is completed, 10 the spindle is threaded through the shell and the case is fitted into the end of the shell and welded thereto as aforementioned. Next, the spindle is tightened into place by threading the nut 21 tightly against the bushing 18. In this 15 tightening operation, it is important that the spindle be held firmly against being turned relative to the shell so as to prevent torsional strain from being exerted on the lead wire 26. For this purpose the bushing 18 is slotted lengthwise at 31 (Figures 4 and 5) so that the initial forcing of the tapered end of the bushing into the flared opening of the shell will compress the bushing tightly against the spindle and hold the latter from turning relative to the bushing.

20 Although the glow plug of the present invention is particularly adapted for use in the precombustion chambers of diesel engines, it will be understood that the present plug may have many other applications. Accordingly, no unnecessary 25 limitation to use in engines is intended by the reference in the preamble of the claims to an engine combustion chamber.

30 The foregoing description is intended to be 35 illustrative and not limitative of our invention since the glow plug herein particularly shown and described, while being a preferred embodiment, is subject to changes and modifications without departure from the scope of our invention, which we endeavor to express according to the following 40 claims.

We claim:

1. A glow plug for use in an engine combustion chamber comprising a cylindrical resistance coil, a cylindrical protective case for said coil, and a tubing of insulation lining the interior 45 peripheral wall of said case for effectively insulating the coil from the case along the length of the coil without materially decreasing the thermal conductivity between the coil and the case, said insulating tubing comprising a sheet of mica of 50 approximately .001" thickness wound several turns on itself into tubular form to a wall thickness between .005" and .007", and said coil having a normal diameter slightly less than the inside 55 diameter of said tubing to permit the coil to be inserted slidably into the tubing without longitudinal displacement of the turns of the coil relative to each other.

2. A glow plug for use in an engine combustion 60 chamber comprising a metal cylindrical case having a wall at one end, a tubing of electrical insulation lining the inside peripheral wall of said case and comprising a sheet of heat resistant insulating material of the order of .001" thickness 65 wound several turns on itself to a wall thickness of the order of .005" to .007", a cylindrical resistance coil in said case having a spacing between adjacent turns thereof, the inner end portion of said coil in said case being bent along a 70 diameter line of the coil to form a lead wire adjacent the end wall of the case and said coil having a normal outside diameter slightly less than the inside diameter of said tubing to permit the coil to be slid into the tubing without longitudinal 75 displacement of the turns relative to each other,

a metal bead on said lead wire in a position substantially at the axis of the coil and welded along said axis both to the lead wire and to said end wall, and an insulating cement in said case between adjacent turns of said coil and in bonded relation with said insulating tubing for holding the turns of the coil permanently in place.
